(74) Attorney, Agent, or Firm—Robert Platt Bell

(57) **CLAIM**

The ornamental design for a CD card, as shown and described.

DESCRIPTION

FIG. 1 is a top plan view of a CD card showing my new design;

FIG. 2 is a bottom plan view thereof;

FIG. 3 is a front view thereof, the back view is identical;

FIG. 4 is a right side view thereof, the left side being identical;

FIG. 5 is a top plan view of a second embodiment thereof;

FIG. 6 is a bottom plan view thereof, the broken line surface ornamentation is for illustrative purposes only and forms no part of the claimed design;

FIG. 7 is a front view thereof, the back view is identical; and,

FIG. 8 is a right side view thereof, the left side being identical.
